UNITED STATES PATENT OFFICE.

ROBERT McC. JOHNSTONE, OF ROSELLE PARK, NEW JERSEY, ASSIGNOR TO CAMERON MACHINE COMPANY, OF BROOKLYN, NEW YORK, A CORPORATION OF NEW YORK.

WINDING MECHANISM.

1,408,742.

Specification of Letters Patent.

Patented Mar. 7, 1922.

Application filed August 25, 1920, Serial No. 405,928. Renewed August 8, 1921. Serial No. 490,729.

To all whom it may concern:

Be it known that I, ROBERT McC. JOHNSTONE, a citizen of the United States, and a resident of Roselle Park, in the county of 5 Union and State of New Jersey, have invented certain new and useful Improvements in Winding Mechanism, of which the following is a specification.

This invention relates generally to winding mechanism, and has more particularly reference to means for controlling a roller such as the top pressure roller forming part 10 of surface rewinding means in a slitting and rewinding machine.

In devices of this character, it has heretofore been customary to provide pinions on 15 the framework and to mount racks for engagement therewith on a vertically movable carriage carrying the top pressure roller. When it was desired to manually lift or lower the carriage mounting the top pressure roller, rotation of the pinions in the proper direction would effect the desired result. It is not, however, always desirable

20 to lift and lower heavy racks, if for no other reason than because, in the arrangement heretofore employed, it is difficult to maintain a given weight to the top pressure roller throughout the winding operation with the result that coils of material are 25 wound under different degrees of pressure at different times during the rewinding operation. A reversal of the usual arrangement is therefore desirable at times. It will be

30 understood, however, that if the racks are stationary on the frames and if the pinions are mounted on the movable carriage, the rise and fall of said carriage will move any operating handle that may be attached to 35 the pinions up or down. This is inconven- 40

venient for the operator because at times the handle may be so high up as to be not readily accessible and also because the operator prefers to have a definite and un- 45

changed position for an operating handle so that he may instinctively, as it were, reach out for the right place. In addition, the operating handle would change its position vertically during operation which would 50 tend to confuse the operator.

The main object and feature of the invention is to so arrange an operating handle for actuating pinions on a movable carriage that it will always occupy substantially the

same position, regardless of the vertical position of the pinions and carriage, and it consists of the features of construction, combination of parts and arrangement of elements hereinafter described, a preferred form of which is disclosed in the accompanying drawings, in which

Fig. 1 is a front elevation, partly broken away, of a winding machine embodying the invention and looking in the direction of the arrow 1 of Fig. 2.

Fig. 2 is a side elevation of the parts shown in Fig. 1 showing the carriage in an upper position.

Fig. 3 is a view similar to Fig. 2 with the carriage in a lower position.

Fig. 4 is a horizontal sectional view on the plane of the line 4—4 of Fig. 1.

Fig. 5 is a detail view of a latch employed in connection with my invention.

Fig. 6 is a sectional view on the plane of 75 the line 6—6 of Fig. 5.

Fig. 7 is a sectional view on the plane of the line 7—7 of Fig. 2.

The form of winding mechanism herein disclosed consists of front and rear rewinding drums 1 and 2, a rewind shaft 3 and a top pressure roller 4. It will be understood that the rewind shaft is displaced upwardly as the rewound material accumulates and is to that effect provided with reduced portions 5 that extend into slots in sliding member 6. Top pressure roller 4 is likewise displaceable vertically by the rise of the rewound material and is mounted in a carriage 7 sliding on the vertical guides 8. 90 Sliding members 6 are carried by carriage 7 and slide in guide members 9 on the framework. Carriage 7 is provided with tie rod 10 and pinion shaft 11 extending transversely of the machine and has plates 12 95 (Fig. 4) that engage the rear face of guides 8. 13 indicate pinions mounted on the pinion shaft to engage upright racks 14 on the front face of guides 8. It is customary to drive the top pressure roller and this is 100 accomplished in the present instance by means of a slip friction drive member 15 vertically movable with the carriage and sliding on splined driving shaft 16. Slip friction drive member 15 has a bevel gear 105 engaging bevel pinion 17 on top pressure roller. The amount of pressure of the top pressure roller is regulated by weights 18

carried by flexible connection 19 that pass over sheaves 20 and are attached to the vertically movable carriage.

21 is a stationary support bolted to the framework and carrying at its outer end a stud 22. 23 is a hanger having an elongated slot 24 into which stud 22 extends. This hanger is at one end journaled to the vertically movable carriage, preferably to 10 the pinion shaft, and carries at its other end an actuating shaft 25. Suitable transmission means here taking the form of sprocket wheels 26, 27 and chain 28 connect the pinion and actuating shafts. It will be understood 15 that rotation of handwheel 29 on the actuating shaft will raise or lower carriage 7 and that the rise or fall of pinion shaft 11 will cause hanger 23 to slide and rock on stud 22. The effect of this movement is to maintain 20 the actuating shaft substantially equidistant from the pinion shaft by moving the frame slightly in or out and to keep chain 28 taut. It will be observed that this is accomplished without materially altering the 25 position of actuating shaft 25 which will remain in substantially the same vertical position notwithstanding the movement up or down of pinion shaft 11. Another advantage to be observed in this connection is 30 that the effective pressure of the top pressure roller is not substantially varied by the travel of the parts during the operation of the machine, and also that a multiplicity of gears and shafts is avoided thus insuring a 35 smooth and uninterrupted rise of the top pressure roller. If many gears were employed there would be a tendency to bind and a jerky motion would be produced thus interfering with the smooth rise of the pressure 40 roller and preventing the application of even pressure.

If after raising carriage 7 to a certain position out of contact with the rewound material, say for the purpose of removing the 45 latter, it is desired to retain the carriage in this position, I make use of a latch for preventing backward rotation of the actuating shaft under the influence of the weight of the carriage. This latch may be constructed 50 as follows: 30 is a ratchet mounted fast on shaft 25; and 31 is a pawl pivotally supported on the hanger and normally urged into engagement with the ratchet by pull-spring 32. During normal operation of the 55 machine, that is, when the pressure roller is rising, the pawl may be in engagement with the ratchet and will, owing to the direction of rotation of the parts, click idly over the ratchet, and the same thing will occur when 60 pressure roller is lifted out of contact with the rewound material. If, however, backward rotation is attempted, the engagement of the pawl with the ratchet will prevent it. Mounted on the pawl is a stem provided 65 with a rotatable sleeve 33 having a pro-

jection 34 and a pin 35 is provided on the hanger. If the pawl is now removed from engagement with the ratchet, as shown in Fig. 5, projection 34 may be turned in under pin 35 to retain the pawl in this position, and 70 the pressure roller may then be lowered.

I claim:

1. In winding mechanism, upright guides, a carriage vertically movable on said guides, upright racks on said guides, a transversely 75 extending pinion shaft on said carriage, pinions on said shaft to engage the racks, an actuating shaft mounted parallel with the pinion shaft and independently of the carriage, transmission means between the two 80 shafts, and means for maintaining the actuating shaft substantially equidistant from the pinion shaft in any vertical position of the latter.

2. In winding mechanism, upright guides, 85 a carriage vertically movable on said guides, upright racks on said guides, a transversely extending pinion shaft on said carriage, pinions on said shaft to engage the racks, an actuating shaft mounted parallel with the pinion shaft and independently of the carriage, transmission means between the two 90 shafts, a hanger carrying the actuating shaft, a stationary support for the hanger, and means for moving on its support the hanger 95 toward and away from the pinion shaft by the rise and fall of the latter.

3. In winding mechanism, upright guides, a carriage vertically movable on said guides, upright racks on said guides, a transversely 100 extending pinion shaft on said carriage, pinions on said shaft to engage the racks, an actuating shaft mounted parallel with the pinion shaft and independently of the carriage, transmission means between the two 105 shafts, a hanger carrying the actuating shaft, a stationary support for the hanger, and means for rocking and sliding the hanger on its support by the rise and fall of the pinion shaft.

4. In winding mechanism, upright guides, a carriage vertically movable on said guides, upright racks on said guides, a transversely extending pinion shaft on said carriage, pinions on said shaft to engage the racks, an 115 actuating shaft mounted parallel with the pinion shaft and independently of the carriage, transmission means between the two shafts, a stationary support, and a hanger, for the actuating shaft, having a sliding and 120 rocking movement on the support and journaled on the carriage.

5. In winding mechanism, upright guides, a carriage vertically movable on said guides, upright racks on said guides, a transversely 125 extending pinion shaft on said carriage, pinions on said shaft to engage the racks, an actuating shaft mounted parallel with the pinion shaft and independently of the carriage, transmission means between the 130

two shafts, and means for maintaining the actuating shaft substantially equidistant from the pinion shaft in any vertical position of the latter while retaining it in substantially the same vertical position.

6. In winding mechanism, upright guides, a carriage vertically movable on said guides, upright racks on said guides, a transversely extending pinion shaft on said carriage, pinions on said shaft to engage the racks, an actuating shaft mounted parallel with the pinion shaft and independently of the carriage, transmission members on the two shafts, a flexible transmission connection between the two members, and means for maintaining the flexible transmission member taut notwithstanding changes in the vertical position of the pinion shaft.

7. In winding mechanism, upright guides, a carriage vertically movable on said guides, upright racks on said guides, a transversely extending pinion shaft on said carriage, pinions on said shaft to engage the racks, an actuating shaft mounted parallel with the pinion shaft and independently of the carriage, transmission means between the two shafts, a stationary support, a hanger, for the actuating shaft, having a sliding and rocking movement on the support and journaled on the carriage, a ratchet on the actuating shaft, a pawl on the hanger, means for normally urging the pawl into engagement with the ratchet, means for holding the pawl out of engagement with the ratchet including a pin on the hanger, and a rotatable member having a projection adapted to pass under said pin.

naled on the carriage, a ratchet on the actuating shaft, a pawl on the hanger, means for normally urging the pawl into engagement with the ratchet, and means for holding the pawl out of engagement with the ratchet.

8. In winding mechanism, upright guides, a carriage vertically movable on said guides, upright racks on said guides, a transversely extending pinion shaft on said carriage, pinions on said shaft to engage the racks, an actuating shaft mounted parallel with the pinion shaft and independently of the carriage, transmission means between the two shafts, a stationary support, a hanger, for the actuating shaft, having a sliding and rocking movement on the support and journaled on the carriage, a ratchet on the actuating shaft, a pawl on the hanger, means for normally urging the pawl into engagement with the ratchet, means for holding the pawl out of engagement with the ratchet including a pin on the hanger, and a rotatable member having a projection adapted to pass under said pin.

Signed at the borough of Brooklyn, in the county of Kings, city and State of New York, this 23 day of August, 1920.

ROBERT McC. JOHNSTONE.
